UNITED STATES PATENT OFFICE

HERBERT D. CLEMMONS, OF STURGIS, MICHIGAN, ASSIGNOR TO SCOVILL MANUFACTURING COMPANY, OF STURGIS, MICHIGAN

DESIGN FOR A HANDLE FOR FLUSH TANKS OR THE LIKE

Application filed March 27, 1931. Serial No. 39,270. Term of patent 14 years.

To all whom it may concern:

Be it known that I, HERBERT D. CLEMMONS, a citizen of the United States, residing at Sturgis, in the county of St. Joseph and State of Michigan, have invented a new, original, and ornamental Design for a Handle for Flush Tanks or the like, of which the following is a specification, reference being had to the accompanying drawings forming part thereof, in which—

Fig. 1 is a side elevation,
Fig. 2 is a front elevation, and
Fig. 3 is an end view of the handle element only, showing my new design.

I claim:

The ornamental design for a handle for flush tanks or the like, as shown.
